Inventor

Willis E. Field

By Frank E. Lorraine, Jr.
Attorney

UNITED STATES PATENT OFFICE.

WILLIS E. FIELD, OF GRAND RAPIDS, MICHIGAN.

BOWL CONNECTION FOR DRINKING FOUNTAINS AND THE LIKE.

Application filed May 3, 1920. Serial No. 378,416.

To all whom it may concern:

Be it known that I, WILLIS E. FIELD, a citizen of the United States of America, residing at Grand Rapids, in the county of Kent and State of Michigan, have invented certain new and useful Improvements in Bowl Connections for Drinking Fountains and the like; and I do hereby declare the following to be a full, clear, and exact description of the invention, such as will enable others skilled in the art to which it appertains to make and use the same.

This invention relates to a novel and simple means of connection for the bowls of drinking fountains or the like to the water pipe fixture through which the water passes to the bubbler head, the excess of water falling back and draining from the bowl. The bowls are made from glazed or enameled earthenware, ordinarily, must have a water tight connection with the water supply pipe or fixtures, and such connection should be one which will not put the bowl under undue strain at the point of connection such that it is liable to fracture, and at the same time the connection should be one readily disassembled should it ever become necessary to replace the bowl. It is the primary object and purpose of the present invention to make a connection for bowls of the character noted which is particularly simple, effective, one which may be very quickly and readily disassembled, and one which has no bad effects on the bowl so as to impart strains thereto rendering it liable to breakage. The invention is illustrated in the accompanying drawing and an understanding of the same may be had from the following description, taken in connection with said drawing, in which,

Fig. 1 is a plan view, with the bubbler head partly broken away, showing the bowl attached by means of my invention, and

Fig. 2 is a vertical section taken centrally through a fountain and using the construction of my invention for attaching the bowl in place.

Like reference characters refer to like parts in the different views of the drawing.

In the construction shown, a hollow fixture 1 of metal has an open upper end, a ledge 2 extending inwardly from the sides of the fixture, it with the part 1^a of the fixture above the ledge making an annular seat for the bowl. Water is entered into the fixture through a pipe 3

which enters at one side of the fixture, an integral nipple 4 having a threaded upper end 5 receiving water from the pipe and directing it upwardly, the nipple turning upwardly and passing above the open upper side of fixture 1. Bowl 6 is formed with an open bottom and an annular ring 7 is formed on the bowl around the opening to seat against the ledge 2, while the bowl is further formed with an annular ledge 8 to seat against the upper edges of the part 1^a of the fixture 1. In its upper side the bowl is formed with an annular recess 9 around the opening 10 in the bowl. The nipple 4 extends upwardly through said opening.

A nut 11 threads onto the nipple, being formed with an outwardly extending flange 12 which seats in the depression 9 of the bowl. In the flange a plurality of openings 13 are made. A bubbler head 14 is secured to the nut 11 at its upper end as shown, it being provided with an opening 15 in its upper end through which water coming under pressure through the nipple 4 may pass. The water may be thrown upward for a short distance and fall back into the bowl, draining therefrom through the openings 13 in flange 12 and into the hollow fixture from which it may pass through a waste pipe 16 connected to the lower part of the fixture.

With a construction of the character described, a very secure connection of the bowl to the fixture may be made. It is very easily applied and tightened without the use of tools and may be quite as readily detached. The connection is tight against the escape of water, no leakage of any kind occurring. There is no liability of imposing too severe a strain on the bowl that it will fracture and become useless. The nut 11 is tightened to any desired degree by merely turning the bowl in the proper direction, the nut turning through frictional contact of flange 12 with the bowl. The construction is very simple and has great durability. In practice it has proven exceptionally satisfactory. The invention is defined in the appended claims and I consider myself entitled to all modifications in structure falling within the scope of the claims.

I claim:

1. In a construction of the character described, a hollow fixture having an open

- upper side, a nipple cast integral with the fixture and extending upwardly through the open upper side thereof, a ledge on the inner side of the fixture adjacent to the upper part thereof, a bowl having an opening in its bottom and its periphery seated on the ledge, a nut provided with an outwardly extending flange threaded on to the nipple and bearing against the bowl around the opening therein, said flange having a plurality of openings therethrough, a bubbler head attached to the nut, a pipe for supplying water to the nipple, and a pipe connected to the fixture and leading away therefrom, substantially as described.
2. In a construction of the character described, a hollow fixture having an open upper side, a nipple integral with the fixture and extending upwardly through the open upper side thereof, a bowl having an opening in its bottom seated in the open upper end of the fixture, and a combined nut and bubbler head threaded on the nipple and engaged against the bowl to secure the bowl in place on the fixture, said nut having passages for the passage of waste water from the bowl into the fixture, substantially as described.
3. In a construction of the character described, a bowl, a bubbler head located in the lower part of the bowl, a fixture through which water passes to the bubbler head, and means to which the head is attached for securing the bowl on the fixture, said means being provided with openings for the passage of waste water from the bowl, substantially as described.
4. In a construction of the character described, a bowl, a fixture under the bowl

against which it seats, a bubbler head located in the lower portion of the bowl, a nut to which the head is attached, means on the fixture extending upwardly into the bowl on to which the nut threads to secure the bowl on the fixture, said nut being provided with a flange having openings therethrough to engage against the bowl, means for carrying water to the head, and a waste pipe connected to the fixture, substantially as described.

5. In a construction of the character described, a hollow fixture having an open upper side, a nipple having a passage therethrough cast integral with the fixture and extending upwardly through the open upper side thereof, an inwardly projecting ledge on the fixture near its upper edges, a bowl provided with an opening through its bottom, an annular recess around said opening on its upper side and a downwardly extending ring around the opening on its lower side located above the fixture, said ring seating against the ledge and entering the upper end of the fixture, the nipple extending upwardly through the opening in the bowl, a nut provided with an outwardly extending flange threaded on to the nipple, said flange entering the recess in the bowl and being provided with openings therethrough, a pipe communicating with the nipple, a pipe connected with the fixture at the lower portion thereof, and a bubbler head having an opening therethrough secured to and above the nut, substantially as described.

In testimony whereof I affix my signature.

WILLIS E. FIELD.
